UNITED STATES PATENT OFFICE.

DAVID MICHIE, OF IRWIN, PENNSYLVANIA.

TRAVELER'S SET.

Application filed December 7, 1922. Serial No. 605,540.

To all whom it may concern:

Be it known that I, DAVID MICHIE, a citizen of the United States, and a resident of Irwin, in the county of Westmoreland and 5 State of Pennsylvania, have invented a new and useful Improvement in Travelers' Sets, of which the following is a specification.

My invention relates to travelers' sets, and it has for its object to provide a relatively simple and compact set that shall comprise an electrically heated device and means for selectively heating a plurality of appliances thereby.

In practicing my invention I provide a 15 box having a hinged cover, with means for holding an electric iron in an inverted position therein. The iron may be energized through a conductor cord in its normal position in the box, and is removable therefrom 20 to permit its use for ordinary ironing operations. A plurality of adapters, located in the box, are removable therefrom to permit of their being located in operative engagement with said iron to hold appliances in 25 heat-receiving relation thereto.

In the single sheet of drawings,

Figure 1 is a top plan view of a device embodying my invention, illustrated with the cover of the box opened;

30 Fig. 2 is a view, in end elevation, of a device embodying my invention, illustrated with one end of the box and of the cover removed;

35 Fig. 3 is a top plan view of an adapter for a curling iron located in its proper operative position on the electric iron;

Fig. 4 is a side view of the members illustrated in Fig. 3;

40 Fig. 5 is an end view of the electric iron and of the adapter illustrated in Fig. 3;

Fig. 6 is a view, in side elevation, of an electric iron and an adapter for permitting the heating of a fluid container thereby and

45 Fig. 7 is a view, in end elevation, of the members illustrated in Fig. 6.

A box 10 may be made of any suitable material, such as wood or sheet metal, and may be of any suitable or desired dimensions and contour. If the box is made of wood it may 50 have a highly finished and ornamental exterior, and if made of metal it may be suitably finished in japan or enamel to give it a pleasing appearance. The box 10 is provided with a suitable cover member 11 connected thereto by a plurality of hinges 12. A hasp 13 on the lid 11, co-operating with a

staple or catch 14 on the box permits of closing the cover and of holding it closed or of locking the same. A suitable handle 15 is provided to permit of carrying the closed 60 box as may be required. In order to limit the opening movement of the cover a suitable ornamental chain 16, having its ends secured respectively to one end of the box and one end of the cover, is provided.

65 Within the box 10 there is located a supporting member or frame 17 of any suitable or desired construction which is adapted to support an electric iron 18 in an inverted position within the box and substantially free 70 and clear of contact with any of the side walls thereof. The height of the supporting frame 17 is such that the working surface of the iron 18, which is removably located in the frame 17, lies above the top of the open 75 box. As the iron may be of any suitable type and forms no part of my present invention, its construction is not further described. A twin conductor cord 19, of the type usually employed with electric irons, is 80 provided to permit of energizing the same from any suitable outlet connected to an electric supply circuit. For this purpose the outer end of the cord 19 is provided with a screw plug member 21 of the usual standard 85 type.

90 A plurality of adapters 22 and 23 are removably located in the box 10, each adapter being normally held therein by a plurality of suitably spaced supporting clips 24. While I have shown the clips 24 secured to the side walls of the box 10, and the adapters 95 22 and 23 as extending longitudinally of the box, this is not essential and is illustrated in order to show a preferred location of the adapters to permit of their being easily and quickly removed from the box and replaced therein.

100 As the working surface or sole plate of the iron 18 is preferably of the usual triangular contour, the adapter 22 is also substantially triangular and conforms in its contour to that of the working surface of the iron. The adapter 22 comprises a sheet metal plate provided with a central and longitudinally extending circularly arched integral portion 25 which is of such diameter as to receive and closely surround the body portion of an ordinary curling iron 26. The member 22 is 105 further provided with depending, integral, flange portions 27 which serve to secure the adapter 22 in close operative relation to the 110

working surface of the iron 18. The arched portion 25 is so located that the curling iron 26 actually engages the working surface of the iron 18 in order that it may be quickly heated thereby.

The adapter 23 comprises a stamped sheet metal member which is also provided with integral depending flange portions 27 as hereinbefore described in connection with 10 the adapter 22, and is further provided with a laterally extending opening 28. The opening 28 is defined by an integral and laterally extending portion of the adapter 23, and may be of any suitable or desired contour and dimensions, but is here shown as substantially circular in contour to receive a metal fluid container or cup 29 which may also be located in the box 10 and held therein by a pair of resilient spring clips 31 secured 20 to one side of the box.

The inside of the cover 11 may be lined with an ornamental cloth such as silk or plush, upon which there may be sewed a plurality of elastic loops 32 which may be 25 employed to hold a plurality of toilet articles. A mirror 33 may also be provided in the lining within the cover 11, the general object of the arrangement being to obtain an ornamental and convenient supporting 30 means for such toilet articles as are usually carried by travelers. If desired, the curling iron 26 may be held in the cover member by a plurality of spring clips 34, or it may be located elsewhere in the box in any convenient position that will permit of its easy 35 and quick removal.

If it is desired to employ the iron 18 for ordinary ironing operations it may be removed from its support within the box, and 40 the plug 21 placed in operative engagement with the ordinary supply circuit outlet, whereby the iron is heated in the usual manner.

If it is desired to heat the curling iron, the 45 electric iron is allowed to remain in its support in the open box and is energized as hereinbefore described. The adapter 22 is slipped over the iron substantially as illustrated in Figs. 3 to 5 of the drawing, and the 50 curling iron is placed in the opening within the arched member 25. As the iron extends above the top of the open box, the curling iron may be slipped into position within the adapter without interference. If it is desired to heat a small quantity of water the 55 adapter 23 is employed, and the container 29 is placed in the opening 28 with its bottom resting upon the working surface of the iron to become heated thereby.

60 While I have illustrated several particular

forms of adapters, I do not desire to be limited thereto, as it is obvious that other forms of adapters may be devised to perform predetermined operations or to heat any one of a variety of appliances. The iron may, of course, also be employed for heating objects or appliances allowed to rest upon or be held close to the flat working surface without any adapter. The type of iron that I have found particularly adapted to a set such as hereinbefore described is relatively small, weighing from one and one half to two pounds. With such an iron, requiring from 80 to 100 watts input, garments of thin cloth can easily be ironed satisfactorily, and the entire weight of the set will not exceed from five to seven pounds.

While an electric iron has been selected as illustrating an electrical heating device, I do not desire to be limited to this, as it is also obvious that any suitable type of electrical heating device may be employed.

Various modifications may be made in the device without departing from the spirit and scope of my invention, and I desire that only such limitations shall be placed thereon as are imposed by the prior art or are specifically set forth in the appended claims.

I claim as my invention:

1. In a traveler's set, in combination, a box, an electrically heated device in said box and removable therefrom, means for permitting the heating of said device in said box, and a plurality of removable adapters for permitting the employment of said device, while in its normal position in said box, in heating other appliances.

2. In a traveler's set, in combination, a box, an electrically heated device located in said box and removable therefrom, means for permitting the heating of said device in said box, and a plurality of removable adapters for holding appliances to be heated by said device while in its normal position in said box, in heat-receiving relation thereto.

3. In a traveler's set, in combination, a box, an electric iron removably mounted in an inverted position in said box, means for permitting the heating of said iron while in said box, and a plurality of removable adapters for holding articles to be heated by said iron in heat-receiving relation to the working surface thereof while the iron is in its normal position in said box.

In testimony whereof, I have hereunto subscribed my name this twenty-ninth day of November, 1922.

DAVID MICHIE.
